UNITED STATES PATENT OFFICE

2,534,688

MULTIUNIT ELECTRON DISCHARGE TUBE

Pierre Marie Gabriel Toulon, Neuilly-sur-Seine, France, assignor to Products & Licensing Corporation, New York, N. Y., a corporation of Delaware

Application July 25, 1947, Serial No. 763,663
In France March 11, 1943

Section 1, Public Law 690, August 8, 1946
Patent expires March 11, 1963

4 Claims. (Cl. 250—27.5)

1

The present invention relates to gas filled thermionic tubes and its object is to provide a tube of this kind including inside a single bulb filled with an ionized gas, a plurality of discharge circuits independent of one another and without reaction upon one another so that the mean potentials of these circuits, each considered as a separate unit may be different from one another.

My invention consists in preventing ionisation around one or several of the cathodes provided in the bulb from spreading beyond certain limits, so as to permit the independent operation, without reciprocal action of the respective cathodes and of the corresponding control systems.

According to my invention, this localizing of ionisation is obtained by interposing between two adjacent circuits one or several supplementary grids or the like kept at a negative potential such that they are more negative than the most negative of the electrodes of the immediately adjacent circuits.

My invention is particularly adapted to the obtainment, in a single bulb, of a thermionic amplifier including several stages in cascade. It permits also of obtaining in a single bulb several thermionic rectifiers having no common cathode. It further applies to the constitution of luminescent tubes and of cathode beam tubes, having a plurality of cathodes. The fact that the discharge circuits are independent permits of establishing between them, on the outside of the tube, any connections as may be found useful for the desired operation.

My invention is particularly useful for producing in a single bulb the arrangements described in my French Patents Nos. 840,915 of January 5, 1938, and 860,481 of June 28, 1939, and their additions.

The single figure of the appended drawings given merely by way of nonlimitative example, discloses the application of the invention to the construction of a multiple rectifier, in a single bulb filled with helium or mercury vapour, such a bulb is particularly interesting for ensuring the flow of the charge stored up in the various condensers of a system of static distribution of the impulses according to the above cited patents.

On a steatite rod 1, indirectly heated by a tungsten pin, through which flows an electric current, I provide independent nickel cylinders covered with baryum oxide 2, 2', 2'' which will act as cathode. Opposite each of these independent cathodes I provide an anode 3, 3', 3'', these various anodes being connected together.

According to my invention, I localize ionisation

2

between each cathode and the corresponding anode, in each of the circuits.

For this purpose, in the example shown, the first circuit includes a grid 4, the second circuit two grids 4' and 4'' and the last circuit one grid 4''', these various grids being connected with the common anode.

Furthermore, I provide two auxiliary grids 5 and 5' between the first and second circuits and 5'' and 5''' between the second and third circuits.

In order to create in space 4—5 an electrostatic field producing the desired localizing of ionisation, concerning the first circuit (rectifier 2—3), grid 5 is negatively biased by means of battery 7 and resistance 6, to be more negative than any of the electrodes 2, 3 and 4.

In an analogous manner, for the second circuit (rectifier 2'—3') grids 5' and 5'' are negatively biased by means of battery 7' and resistances 6' and 6'', to be more negative than the most negative of the corresponding electrodes 2', 3', 4' and 2', 3', 4''.

Finally, for the last circuit (rectifier 2''—3'''), grid 5''' is negatively biased by means of battery 7''' and resistance 6''', to be more negative than any of the electrodes 2'', 3'', 4'''.

Thus, owing to these supplementary grids which supply a suitable electrostatic field, I prevent ionising from going from one cathode to the other; every cathode can therefore work independently, although all of them are contained in a single vessel, which greatly simplifies the construction of the tube.

What I claim is:

1. A gaseous conduction discharge system, comprising, a gas filled container, a first tube section comprising a first anode and a first cathode, a second tube section comprising a second anode and a second cathode, all located within said container, at least one further electrode interposed between said first anode and cathode and said second anode and cathode, each of said anodes and each of said cathodes having a predetermined potential, and means for establishing a further potential for said further electrode, said further potential more negative than the most negative predetermined potential of any of said anodes and cathodes.

2. A gaseous conduction discharge system, comprising, a gas filled chamber, a pair of adjacent gaseous discharge units within said chamber, each of said units comprising an anode and a cathode, means for maintaining said anodes at positive potential with respect to said cathodes, a pair of grids connected between said units, means con-

necting said grids to said anodes, at least one further grid interposed between the grids of said pair of grids, and means for maintaining said at least one further grid biased negatively with respect to said cathodes.

3. A gaseous conduction discharge system, comprising, a gas filled container, a plurality of mutually adjacent gaseous discharge units within said container, each of said units comprising an anode and a cathode, means for maintaining said anodes 10 at a higher potential than said cathodes, means for electrically isolating said units from one another, said last means comprising an electrode interposed between each pair of said units and means for maintaining said electrode at a potential negative with respect to the most negative cathode of each pair of adjacent units.

4. A gaseous discharge conduction system comprising, a gas filled container, a first anode and cathode, a second anode and cathode, and means 20 interposed between said first anode and cathode and said second anode and cathode for preventing

ionization occurring between said first anode and cathode from spreading to said second anode and cathode, said last means comprising a shield electrode interposed between said first anode and cathode and said second anode and cathode, and means for maintaining said shield electrode electro-negative with respect to said cathodes.
